(57) **CLAIM**

We claim the ornamental design for a retractable boat ski tow and eye mast, as shown and described.

DESCRIPTION

FIG. 1 is a right side elevation view of the retractable boat ski tow and eye mast showing my new design in an extended position;

FIG. 2 is a left side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a perspective view thereof; and,

FIG. 8 is a perspective view thereof, showing my new design in a retracted position.

1 Claim, 5 Drawing Sheets

FIG. 1

FIG. 2

FIG. 5

FIG. 6

FIG. 7

FIG. 8
